(57) **CLAIM**

The ornamental design for a patterned glove with a straight cuff, as shown and described.

DESCRIPTION

FIG. 1 is a front elevation view of the patterned glove with a straight cuff in accordance with our design, wherein the glove is for a left hand; and the front elevation view of the glove for the right hand, which is not shown herein, is a mirror image thereof;

FIG. 2 is a rear elevation view of the glove of FIG. 1, wherein the rear elevation view of the glove for the right hand, which is not shown herein, is a mirror image thereof; FIG. 3 is a left side elevation view of the glove of FIG. 1, wherein the left side elevation view of the glove for the right hand, which is not shown herein, is a mirror image thereof; FIG. 4 is a right side elevation view of the glove of FIG. 1, wherein the right side elevation view of the glove for the right hand, which is not shown herein, is a mirror image thereof;

FIG. 5 is a top plan view of the glove of FIG. 1, wherein the top plan view of the glove for the right hand, which is not shown herein, is a mirror image thereof;

FIG. 6 is an enlarged view of the highlighted region of FIG. 1, showing a pattern that is provided on the gripping surfaces of the glove; and,

FIG. 7 is an enlarged cross-section of the pattern taken along line 7-7 of FIG. 6.

The broken lines in the drawings show the environment in which the design is used. The broken lines form no part of the claimed design.

The dot-dot-dash lines show the boundary of the highlighted region of FIG. 1 and form no part of the claimed design.
